UNITED STATES PATENT OFFICE.

CHARLES H. NORTON, OF WORCESTER, MASSACHUSETTS, ASSIGNOR TO NORTON
GRINDING COMPANY, OF WORCESTER, MASSACHUSETTS, A CORPORATION OF
MASSACHUSETTS.

GRINDING-MACHINE.

1,164,745.

Specification of Letters Patent. Patented Dec. 21, 1915.

Original application filed June 6, 1913, Serial No. 772,054. Divided and this application filed July 21, 1914. Serial No. 852,286.

To all whom it may concern:

Be it known that I, CHARLES H. NORTON, a citizen of the United States, residing at Worcester, in the county of Worcester and 5 State of Massachusetts, have invented a new and useful Grinding-Machine, of which the following is a specification.

This invention relates to a grinding machine and particularly to improved means 10 for supporting the grinding wheel slide in a surface grinding machine, this application being a division of applicant's prior application, Serial No. 772,054, filed June 6, 1913.

In a surface grinding machine it is customary to mount the grinding wheel upon a 15 shaft extending at right angles to the line of travel of the table and it is necessary to so support this shaft that the wheel may be projected forwardly over any point on the 20 surface of the table. In certain positions, therefore, the wheel must overhang its support for a considerable distance, and special provision must be made to insure the necessary rigidity of the wheel shaft.

It is the principal object of my present 25 invention to provide improved devices for thus supporting the grinding wheel and the slide upon which it is mounted by the use of which greatly increased rigidity is secured.

A further object of my invention is to 30 provide means by which the wheel slide may be quickly and accurately adjusted, said means providing for rapid approximate adjustment of the slide and for slower and more accurate final adjustment.

A still further object of my invention is 35 to provide a construction in which the wheel slide is fully protected from dirt and injury.

With these objects in view my invention 40 contemplates the provision in a grinding machine of a rigid longitudinally-extended overhanging support or hood, within and 45 beneath which the wheel slide is mounted for longitudinal movement. Suitable provision is made for the vertical adjustment of the hood either by hand or power and for the longitudinal adjustment of the slide 50 within the hood.

My invention further consists in certain 55 devices, arrangements and combinations of parts which will be hereinafter described

and more particularly pointed out in the appended claims.

55

A preferred form of my invention is shown in the drawings in which—

Figure 1 is a front view of a machine 60 constructed in accordance with this invention; Fig. 2 is a side elevation of the machine shown in Fig. 1; and Figs. 3 and 4 are detail views of the devices for adjusting the wheel slide longitudinally.

The machine shown in the drawings comprises a main body or frame 2 carried by 65 supports 3 each consisting of a wedge-shaped member having ears 4 extending up therefrom, the bed itself being supported upon these wedges. Adjusting screws 5 provide means for moving the wedges relatively to 70 the bed whereby the ways 7 may be brought into accurate alinement. The work supporting table 8 is mounted for longitudinal movement upon the ways 7 and suitable operating devices are provided for moving the 75 table 8 longitudinally and for automatically reversing the travel of the table, the reversing mechanism being controlled by dogs 9 adjustably secured to the table 8. These operating devices constitute no part of my 80 present invention and for a full description thereof reference is made to my original application.

A standard 10 is mounted upon the bed 2 and upon its right hand face is provided 85 with vertical bearing surfaces 11. An overhanging hood or support 12 is mounted for vertical movement upon the bearing surfaces 11. A vertical feed screw 13 is mounted in the standard 10 and extends through a 90 threaded hole in the hood 12. At its upper end the screw 13 is connected by beveled gears to an inclined shaft which in turn is connected through suitable gears to a hand wheel 14 by which the hood 12 may be raised 95 and lowered. Suitable connections are also provided by which the hood may be raised and lowered by power. All of the devices for vertically moving the hood are fully described and claimed in my original application above designated.

The hood 12 is longitudinally extended on each side of the bearing surface 11, as clearly shown in Fig. 2, the extended portions of the hood having a substantially semi-cylindrical 105 upper surface. On its lower side the hood

is provided with a pair of horizontal inwardly extending projections or ways 15 upon which is supported the wheel slide 16. Additional bearing surfaces 17 are also provided upon the hood which coöperate with inclined bearing surfaces on the upper face of the wheel slide, whereby the slide is securely confined for longitudinal movement only.

- 10 Depending members 18 are formed upon the slide 16 and support bearings 19 for the wheel shaft 20 carrying the wheel W upon its forward end. The shaft 20 also carries a pulley 21 driven by a belt 22 from a wide-faced pulley 23. The pulley 23 is mounted in a swinging frame 24 pivoted to a bracket 25 which is secured to a downwardly extending projection of the hood 12 and is movable vertically therewith. At its outer end 20 the swinging frame 24 is spring-connected to a rod 26 which in turn is secured to the outer portion of the hood 12, provision being made for vertical adjustment of the rod 26. The pulley 23 may have any suitable 25 connection to the main power shaft of the machine which will permit vertical adjustment of the pulley 23, one form of such connection being clearly shown in the original application.
- 30 With the construction it will be seen that the belt 22 can travel longitudinally along the wide-faced pulley 23 as the wheel slide is moved forward and back, while the driving connections for the pulley 23 permit vertical adjustment of the hood 12 upon the support 10. For the longitudinal adjustment of the wheel slide, the slide is provided with a rack 30 meshing with a pinion 31. The pinion 31 is mounted upon a short horizontal shaft 32 connected by beveled gears 33 and 34 to a forwardly extending horizontal shaft 35. The forward end of the shaft 35 is supported in a casing 36 mounted on a bracket 37 secured to the hood 12. A hand 40 wheel 38 is keyed to the forward end of the shaft 35 and constitutes means for rapidly adjusting the wheel slide longitudinally through the medium of the beveled gears 33 and 34 and the rack and pinion 30 and 31.
- 45 For the more accurate adjustment of the wheel slide, a worm wheel 40 is loosely mounted on the shaft 35 and meshes with a worm 41 upon a short shaft 42 supported in bearings in the casing 36 and having a hand 50 wheel 43 mounted thereon. A flanged collar 44 is secured to the shaft 35 upon one side of the worm wheel 40 and a second flanged collar 45 is slidably keyed to the shaft 35 upon the opposite side of the worm wheel. A 55 tightening nut 46 constitutes means for forcing the collar 45 against the worm wheel thus binding the wheel between the two flanged collars. When thus secured the shaft 35 may be slowly rotated by means of

curate final adjustment of the wheel slide may be easily secured.

A water guard or shield 50 is mounted upon the hood 12 for vertical movement therewith. The guard 50 is provided with an upwardly extending rod 51 which is vertically adjustable in a clamp 52. The clamp 52 is pivotally connected at 53 to a link 54 which in turn is pivoted at 55 upon a casting 56 mounted upon the hood 12. At the 75 pivots 53 and 55 the parts are connected by friction joints so that the shield 50 may be easily and quickly moved to any desired position without the necessity of using tools for this adjustment.

The operation of the machine herein described is thought to be clearly apparent, the work being secured upon the table 8 and being moved longitudinally thereby beneath the grinding wheel W. The wheel is vertically adjusted through the medium of the vertical feed screw 13 and is thereby brought into proper relation with the work. The wheel may also be adjusted laterally by the devices herein described so that it will operate over any desired portion of the table surface.

Having thus described my invention it will be evident that changes and modifications can be made therein by those skilled in the art without departing from the spirit and scope thereof as set forth in the claims and I do not wish to be limited to the details herein disclosed, but

What I do claim is:—

1. In a grinding machine, in combination, a standard, a hood mounted to slide thereon, a wheel slide supported beneath said hood and longitudinally movable therein, a grinding wheel rotatably mounted beneath said slide, and means for moving said slide longitudinally.

2. In a grinding machine, in combination, a standard, a hood adjustably supported on said standard, and a wheel slide movable beneath said hood, said slide being supported on ways beneath said hood, and said slide and ways being entirely covered and protected by the hood.

3. In a grinding machine, in combination a standard, a hood adjustably supported on said standard, said hood being longitudinally extended on each side of said standard and having depending sides, a wheel slide movable beneath said hood, and means on said depending sides for supporting and guiding said slide.

4. In a grinding machine, in combination, a standard, a hood vertically movable thereon, said hood having opposite inwardly projecting ways in its lower portion, a wheel slide longitudinally movable in said ways, a grinding wheel mounted on said slide, and means for rotating said wheel.

- a standard, a hood adjustably supported on said standard, said hood having a substantially semi-cylindrical surface with a convex top and a substantially flat lower portion, and a wheel slide mounted for longitudinal movement beneath said hood, and slideable within the lower portion thereof. 5
6. In a grinding machine, in combination, a standard, a hood mounted to slide thereon, a wheel slide supported beneath said hood and longitudinally movable therein, a grinding wheel rotatably mounted beneath said slide, and means for moving said slide longitudinally, said means comprising means 10 for rapid preliminary adjustment of said slide and additional means for accurate final adjustment thereof. 15
7. In a grinding machine, in combination, a standard, a hood adjustably supported on said standard, a wheel slide longitudinally movable in said hood, a wheel shaft mounted in bearings secured beneath said slide, a grinding wheel and a driven pulley on said shaft, an intermediate shaft mounted to 20 move vertically with said hood, said intermediate shaft being supported parallel to the line of travel of the wheel slide and having a wide-faced pulley thereon, means for driving said intermediate shaft, and a belt 25 connecting the wide-faced pulley to the pulley on the wheel shaft and effective to drive the latter. 30
8. In a grinding machine, in combination, a standard, a hood adjustably supported on said standard, a wheel slide longitudinally movable in said hood, a wheel shaft mounted in bearings secured beneath said slide, a grinding wheel and a driven pulley on said shaft, an intermediate shaft mounted to 35 move vertically with said hood, said intermediate shaft being supported parallel to the line of travel of the wheel slide and having a wide-faced pulley thereon, means for driving said intermediate shaft, and a belt 40 connecting the wide-faced pulley to the pulley on the wheel shaft and effective to drive the latter. 45
- the latter, said intermediate shaft being supported in a vertically swinging frame having an adjustable yielding connection with said hood. 50
9. In a surface grinding machine, in combination, a bed, a work table movable thereon, a standard fixed to said bed, a hood supported by said standard, a horizontally movable wheel slide mounted on said hood, a grinding wheel rotatably supported on said slide and a guard plate mounted on said hood and adjustable with relation to said wheel and table. 55
10. In a surface grinding machine, in combination, a bed, a work table movable thereon, a standard fixed to said bed, a hood supported by said standard, a horizontally movable wheel slide mounted on said hood, a grinding wheel rotatably supported on said slide, a member carried by said hood and adjustable relatively thereto, a guard plate adjustably mounted on said member, and friction devices to hold said member and said plate in adjusted position relative 60 to said hood and to each other. 65
11. In a surface grinding machine, in combination, a bed, a work table movable thereon, a standard fixed to said bed, a hood supported by said standard, a horizontally movable wheel slide mounted on said hood, a grinding wheel rotatably supported on said slide and a guard plate mounted on said hood and adjustable with relation to said wheel and table, said plate being vertically 70 se adjustable in a clamp, and said clamp being secured to said hood by a swinging link, said link being held in adjusted position with reference to said hood and said clamp by friction joints. 75
- In testimony whereof I have hereunto set my hand, in the presence of two subscribing witnesses.

CHARLES H. NORTON.
